CLAIM

The ornamental design for an anchor for an accessory attachable to an oscillating multi-tool, as shown and described.

DESCRIPTION

FIG. 1 is a top perspective view of a first embodiment of an anchor for an accessory attachable to an oscillating multi-tool.

FIG. 2 is a bottom perspective view of the anchor shown in FIG. 1.

FIG. 3 is a right side view of the anchor shown in FIG. 1.

FIG. 4 is a left side view of the anchor shown in FIG. 1.

FIG. 5 is a rear view of the anchor shown in FIG. 1.

FIG. 6 is a front view of the anchor shown in FIG. 1.

FIG. 7 is a top of the anchor shown in FIG. 1.

FIG. 8 is a bottom of the anchor shown in FIG. 1.

FIG. 9 is a top perspective view of a second embodiment of an anchor for an accessory attachable to an oscillating multi-tool.

FIG. 10 is a bottom perspective view of the anchor shown in FIG. 9.

FIG. 11 is a right side view of the anchor shown in FIG. 9.

FIG. 12 is a left side view of the anchor shown in FIG. 9.

FIG. 13 is a rear view of the anchor shown in FIG. 9.

FIG. 14 is a front view of the anchor shown in FIG. 9.

FIG. 15 is a top of the anchor shown in FIG. 9.

FIG. 16 is a bottom of the anchor shown in FIG. 9.

FIG. 17 is a top perspective view of the first embodiment of an anchor for an accessory attachable to an oscillating multi-tool.

FIG. 18 is a bottom perspective view of the anchor shown in FIG. 17.

FIG. 19 is a right side view of the anchor shown in FIG. 17.

FIG. 20 is a left side view of the anchor shown in FIG. 17.

FIG. 21 is a rear view of the anchor shown in FIG. 17.

FIG. 22 is a front view of the anchor shown in FIG. 17.

FIG. 23 is a top of the anchor shown in FIG. 17.
